UNITED STATES PATENT OFFICE.

FRANK H. DICKSON, FRANCIS F. DICKSON, AND ADRIAN J. DICKSON, OF AUBURN,
NEW YORK.

ROUNDABOUT.

Application filed December 3, 1926. Serial No. 152,469.

This invention relates to that class of teeter-boards or seesaws in which the teeter-board or beam is mounted to rotate about as well as rock on its support, and the objects are to provide a simple and efficient support which will permit the teeter-board to be easily adjusted to carry children differing in weight, to provide a support which may be folded into a small compass when not in use and yet will not collapse when in use, and to provide means whereby the end of the beam will be caused to glide when it strikes the ground instead of coming to a sudden stop. These stated objects and other objects which will hereinafter appear are attained in such a structure as is illustrated in the accompanying drawing, and the invention resides in certain novel features which will be particularly pointed out in the appended claim.

In the drawing, Figure 1 is a side elevation of an apparatus embodying the invention,

Figure 2 is a side elevation on a larger scale of the upper part of the support,

Figure 3 is a top plan view of the tripod head,

Figure 4 is an enlarged section of the socket member in which the pivot post engages,

Figure 5 is a section on the line 5—5 of Figure 4,

Figure 6 is a plan view of the socket member,

Figure 7 is a detail of the end of the beam or teeter-board,

Figure 8 is a detail showing a modification.

The apparatus consists of a beam or teeter-board 1 and a tripod on which the beam is mounted, the beam being equipped at its ends with seats 3 and gripping posts or handles 4. The tripod comprises legs 5 and a head 6 to

which the legs are attached. The head is a single integral casting having a central post 7 of circular sectional contour and tapering upwardly to its semi-spherical terminal as shown in Figs. 2 and 3, and three arms 9 radiating from the lower end of the post, said arms being substantially triangular in form and each provided on one side near its outer corner with a lateral stop lug 10 and, on the same side, at its upper corner with a shoul-

der 11 which will overhang the upper end of the attached leg. The legs are pivoted to the sides of the respective arms, as at 12, and bear upwardly directly against the stop lugs and the shoulders when in use so as to carry the weight of the apparatus and its riders. When

not in use, the legs may be swung upon their respective pivots to bear flat against the vertical side of the next adjacent arm so that their lower ends will be brought close together, the outwardly swinging upper corners of the legs being accommodated in the spaces 13 between the corresponding stop lugs and shoulders. Braces 50 are preferably provided to insure against spreading of the legs when in use, each leg being provided with an eye 51 in which a brace is hung and each brace having a hook 51^a at its free end to engage in the eye on another leg. There is thus provided a brace on each side of the tripod.

The tapered pin or post 7 extends into a central longitudinal slot in the teeter-board and engages in a socket member or saddle 14 therein. Said socket member is a casting having the general form of an arch, the sides and crown of which are channeled, as indicated at 15, with the ends rising from an anchoring base plate 16 having a central longitudinal slot 17 to accommodate the post 7 and provided with openings 18 at proper

points through which securing devices may be inserted into the beam or board 1. The socket member fits within the longitudinal slot of the board or beam and the anchoring base plate bears against the under side of the board, as will be understood, at the sides of the slot, while in the under side of the crown portion of the member is a longitudinal series of depressions or sockets 181 any one of which may be engaged over the post 7. When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

When a socket 181 is engaged upon the post, the beam or board may rock upon the post and also swing about the same, and by selectively engaging the sockets upon the post the board will be so adjusted as to compensate for the unequal weights of the riders seated on its opposite ends. Bolts 100 may be inserted through the beam transversely in position to bear against the ends of the saddle and aid in maintaining the saddle and the beam in fixed relation. It will be noted that the post does not project through the saddle but is housed in the saddle which rests on the extreme upper end of the post without being secured thereto, the saddle being, in turn, housed in the beam. The saddle is protected from damage by chance blows and the apparatus is given a very neat appearance. To dismantle the apparatus, it is necessary merely to lift the board from the post and it may be returned to position just as easily.

At each end of the teeter-board or beam is secured a transverse plate 19 provided with an outwardly projecting stud 20 upon which is journaled a roller or rolling shoe 21, the 5 diameter of the roller being such that the periphery thereof will project somewhat below the bottom of the beam. The roller may be retained upon the stud 20 by any convenient means and it may be described as frus- 10 toconoidal in form, the periphery being thereby disposed so as to avoid the presentation of any angle or sharp edge to the ground. When the end of the teeter-board strikes the ground, the impact will cause 15 rotation of the roller with a resultant gliding of the board laterally instead of bringing the board to a sudden stop with its attendant risk of dislodging a child seated on the end of the board. Possible injury to the users of 20 the apparatus is thus avoided.

Instead of the rolling shoe 21, the runner or sliding shoe 200 may be used.

Having fully described our invention, what we claim as new and desire to secure by Letters-Patent, is:—

A roundabout comprising a support, a co- 25 nodial pivot post rising from the support and having a semispherical upper end, a teeter-board provided with a longitudinal slot receiving the pivot post, and a saddle secured to the teeter-board and housed within the slot therein over the post, said saddle being in the form of an arch internally channeled and provided in the under side of its crown 30 with a longitudinal series of sockets selectively engageable over the top of the post, the post being housed in the saddle.

In testimony whereof, we have signed this specification.

FRANK H. DICKSON.
